CLAIM

The ornamental design for a support device, as shown and described.

DESCRIPTION

FIG. 1 is a front perspective view of a support device, showing my new design;

FIG. 2 is a top view thereof;

FIG. 3 is a bottom view thereof;

FIG. 4 is a right view thereof;

FIG. 5 is a left view thereof;

FIG. 6 is a front view thereof;

FIG. 7 is a rear view thereof; and,

FIG. 8 is a top view thereof, shown in an environment of use. The broken line showing of a hanging hook in FIGS. 1-5 and 8 and a rectangular support in FIG. 8 depicts environment. The remaining broken lines shown in the figures depict portions of the support device. The broken lines form no part of the claimed design.
